BOWLING PIN CONVEYING MECHANISM
 Henry C. Congelli, Stamford, Conn., assignor to American Machine & Foundry Company, a corporation of New Jersey

Filed Dec. 26, 1957, Ser. No. 705,239
 14 Claims. (Cl. 273—43)

This invention relates to automatic bowling pin spotting machines and more particularly to novel means for conveying bowling pins from the pit of a bowling alley to a delivery station for delivery to a pinspotting device for placement on the playing bed of a bowling alley.

The invention in general comprises improvements to existing types of bowling pin conveying mechanisms for use with bowling pins from the pit of a bowling alley to an elevated discharge station thereabove, and especially to the elimination of positively actuated grippers which must be positively actuated in order to progressively grip pins as they are delivered into the conveyor. In accordance with the present invention, the means for holding pins which are delivered into the conveyor are gravity operated and are effective to hold pins in the conveyor as the result of the travel of the conveyor upwardly and the concomitant gravity biased action of the holding means as they move progressively into holding engagement with pins positioned in the conveyor.

The conveyor embodying the invention consists of an annular wheel provided with a series of pockets, each pocket having associated therewith a gravity operated pin gripping or holding arm so constructed and arranged that as the result of the rotary motion of the wheel, each arm is gravity biased or moved into engagement with a pin seated in the pocket with which the particular arm is associated, and the pin is so held from the point at which the arm becomes operative until the pin held thereby reaches a predetermined delivery station where it is discharged.

It is therefore an object of the present invention to provide a pin elevating member provided with novel pin securing means.

It is also an object of this invention to provide a pin elevating member employing self-actuating means for securing pins in the respective pockets thereof.

An additional object of the invention is to provide a pin elevating member provided with gravity actuated pin holders to selectively grip pins carried in the pin elevating member.

A further object of the present invention is to provide pin holding rods mounted for gravity bias operation with pins retained in the pockets of a rotary pin elevating member.

It is an added object of this invention to provide a rotary pin elevating member employing gravity actuated pin securing means operative to selectively release pins from the elevating member at a predetermined location on its path of travel.

It is an object of the invention to provide an improved bowling pin elevating device comprising an annular wheel wherein the wheel is provided with a channel having a plurality of pin receiving seats or pockets and novel pin holding and releasing means associated with each of said seats or pockets for holding pins therein from the point of receipt of pins in each pocket until the wheel has moved to locate each seat or pocket carrying a pin at a predetermined elevated point of delivery above the pit whereupon such pin is released by the gravity biased action of holding means and is free to fall into a distributor for delivery to a pin setting mechanism.

With these and other objects not specifically mentioned in view, the invention consists in certain combinations and constructions which will be hereinafter fully described

and then specifically set forth in the claims hereunto appended.

In the accompanying drawings which form a part of this specification and in which like characters of reference indicate the same or like parts:

5 FIG. 1 is a front view of a rotary pin elevating member provided with a preferred embodiment of the invention.

10 FIG. 2 is a partial sectional view of a preferred embodiment of the invention, and

FIG. 3 is a partial front view of the mechanism shown in FIG. 2.

15 FIG. 4 is a partial front view of a rotary pin elevating member provided with a modified form of the invention.

Referring to FIGURE 1, pin elevating member designated generally 10, is shown installed in the pit P of a conventional bowling alley at one side of the pit, preferably at the rear thereof and between kickbacks K1 and K2 of the present invention. Pin elevating member 10, provided with a preferred embodiment of the invention, is mounted on and rotates with hub 12 which is rotatably mounted on shaft 14. Shaft 14 is fixed in frame 16 which, in turn, is suitably secured to kickbacks K1 and K2 adjacent the sides of pit P. Pin elevator 10 is preferably formed of sheet metal parts or sections, although light castings, or other comparable material may be used to function as desired. The center of body portion 18 of pin elevator 10 is substantially conical in form, and provided with a circular marginal generally U-shaped rim or channel 20. The periphery of channel 20 is flanged forming groove 22 to accommodate endless belt 24. Belt 24 is driven by sheave 26 secured to and rotating with shaft 28 which is driven in any suitable manner (not shown).

30 35 Channel 20 is of a width and depth sufficient to accommodate bowling pins delivered thereto from the pit P of the bowling alley. Blocks or fillers 29, secured to and equidistantly spaced in channel 20, provide suitable pin pockets or seats 30 therein.

40 45 Seven pockets have been found to operate satisfactorily, and for the purpose of illustration, are shown in FIGURE 1. If desired, more or less than seven pockets can be provided depending upon the diameter of rotary pin elevator 10 and the length of bowling pins to be handled; namely, tenpins, duck pins, or others.

50 55 Endless conveyor 31 is mounted for travel in pit P around rollers 33 secured to shafts 32, only one of each being shown for convenience (see FIG. 1). Shafts 32 are mounted transversely in pit P at the front and rear thereof in bearings 34 and are driven in any convenient manner. Frame member 36 and 38 are secured to kickbacks K1 and K2, respectively, and support bearings 34. Platform 40 is secured to sides 42 and 44, as shown in FIG. 1, preventing the upper lap of conveyor 31 from sagging under the weight or impact of bowling pins deposited thereon from the playing surface of the alley. Sides 42 and 44 are secured to frame members 36 and 38, respectively, in the inclined manner shown in FIG. 1. Chute 46, secured transversely in pit P to kickbacks K1 and K2, is positioned in the space between the edge of conveyor 31 and pin elevator 10, providing a continuous smooth surface therebetween.

60 65 Bowling pins removed from the playing surface of the associated bowling alley either by play or by a suitable sweep mechanism are deposited upon the upper lap of conveyor 31 which is preferably in continuous motion in pit P. Pins thus deposited are carried on conveyor 31 rearwardly of pit P toward pin elevator mechanism 10. Bowling pins removed from the playing surface of the associated alley which land on sides 42 and 44 in pit P will slide or gravitate thereon onto conveyor 31 to be delivered to pin elevator 10 also. Plows 48 and 50 are

secured in any convenient manner to kickbacks K1 and K2 adjacent sides 44 and 42, respectively, adjacent pin elevating member 10, as shown in FIGURE 2. Plows 48 and 50 operate to direct pins which land on sides 44 and 42 away from the corners formed at kickbacks K1 and K2 and pin elevating member 10 and onto conveyor 31.

Pins deposited on conveyor 31 are delivered as described hereinabove over chute 46 to pin elevating mechanism 10 at station I, see FIGURE 1. The face of chute 46 preferably is at the same angle as the peripheral wall of channel 20 to allow pins delivered upon conveyor 31 to roll over chute 46 into one of the pin pockets 30 of pin elevating member 10. Pin channel 20 is so formed that it readily and easily receives pins lying lengthwise along and within channel 20 or with the axes of the pins lying in a plane generally transverse to the axis of rotation of pin elevator 10. Actually pins cannot be properly supported in pin elevating member 10 for elevation to station III in any other position. It will also be noted that the grooves 22 incline inwardly towards the axis of rotation of pin elevator 10 and forwardly with respect to the alley so that channel 20 faces in the direction from which the pins approach as they are urged rearwardly over chute 46 by conveyor 31. Pins thus become seated in pockets 30, either butt end first or handle end first, without the assistance of mechanical adjuncts and are carried upwardly toward discharge station, station III, in the direction indicated by arrow A as the rotation of pin elevator 10 travels each pocket 30, in succession through pit P and past stations I and II.

Pin elevating member 10 and its associated mechanism may be similar in construction and operation to that shown in Holloway et al., Patent No. 2,767,983. Further detailed disclosure thereof, except as is necessary for an understanding of the present invention, is omitted in the interests of brevity.

As pin elevating mechanism 10 travels a pocket 30 with a pin 68 residing therein from pick-up station I toward discharge Station III, gravity will tend to dislodge pin 68 from its seated position in pocket 30. Clamp rods or pin holders 56 operate to prevent this. A clamp rod or pin holder 56 is provided for each pocket 30 and is pivotally mounted adjacent its midpoint on stud 58 (FIGURE 2). Stud 58 in turn is fixed on bracket 60 secured to pin elevating member 10. A counterweight 62 is fixed to one end of each of the clamp rods 56, as shown in FIGURE 1. However, if preferred, counterweight 62 could be formed integrally with clamp rod 56.

As a particular pocket 30 with a pin 68 seated therein is moved away from station I toward station III, its associated clamp rod 56, at approximately station II, will pivot about stud 58 in a clockwise direction as viewed in FIGURE 1, due to the pendulum-like action of counterweight 62. Rod 56 will rest against stop 64 secured to bracket 60 which limits the clockwise rotation of rod 56. Pin 68 seated in pocket 30 will be engaged by the end of rod 56 remote from counterweight 62 as rod 56 pivots into operative position and comes to rest against stop 64 and is secured thereby against removal from pocket 30, as illustrated in FIGURE 1.

Pins 68 thus secured in pocket 30 of pin elevator 10 will remain therein until the particular pocket 30 arrives at station III. At station III, release means is provided to effect the selective release of pins 68 from the pin pockets 30 since during the cyclic operation of the machine it is periodically desired to retain pins in pockets 30 and not discharge them at station III into the already full pinspotting units of the associated machine.

This release means comprises a solenoid 72 secured to bracket 76 of the machine, as shown in FIGURE 2. When, during the cyclic operation of the associated machine, it is determined by a control system (not shown) that pins 68 are not to be released at station III, a circuit is completed energizing solenoid 72. Solenoid 72,

when energized, retracts its armature 74 out of the path of travel of a rod 56 so that it remains in operative pin engaging position as its associated pocket 30 is rotated past station III. Pins 68 thus remain clamped in pocket 30 until they pass between station III and on their return trip back to station I. Between station III and station IV, a clamp rod 56 will now pivot about stud 58 in a counter-clockwise direction as viewed in FIGURE 1 due to the pendulum-like action of counterweight 62, bringing rod 56 to rest adjacent stop 64. Stop 64 secured to bracket 60 opposite stop 66 limits the counter-clockwise rotation of rod 56. Pins 68 thus released by rod 56, are retained in pocket 30 by guide rail 70 secured to suitable framework (not shown) adjacent pin elevating member 10 until it is re-conveyed thereby to station I.

Rod 56 remains in inoperative position adjacent stop 64 as its associated pocket is moved from station IV past station I. It will be apparent that in this position, rod 56 is fully retracted from pocket 30 thus permitting a pin to enter pocket 30 completely unhindered.

When during the cyclic operation of the associated machine, it is desired to release pins 68 at station III, the control system (not shown) breaks the circuit energizing solenoid 72. When solenoid 72 is de-energized, its internal spring (not shown) would extend armature 74 into the path of travel of a rod 56, as shown in FIGURES 2 and 3. As rod 56 contacts armature 74 as it and its associated pocket 30 are moved past station III, rod 56 is pivoted in a counter-clockwise direction, as viewed in FIGURE 3, releasing pin 68. Pin 68, thus released, gravitates out of pocket 30 into pin receiving and aligning device 80 suitably secured to framework (not shown) by bracket 82 at station III, as shown in FIGURES 1, 2 and 3. Pin receiving and aligning device 80 may be similar in construction and operation to that shown in Zuercher patents numbered 2,767,984 and 2,769,637. Since device 80 forms no specific part of the present invention, further disclosure thereof is omitted.

If desired, the pin discharge station can be moved 40 from its position at station II directly above pin pick-up station I to a position on the return or downward path of travel of the pin carrying pockets 30; for example, between the twelve and three o'clock positions thereof as shown in FIG. 4. In this modified form of the invention, the pin engaging rods 56 are biased by gravity away 45 from the pin conveying channel 20 at the discharge station, thereby effecting the automatic release of pins from channel 20. If this change in position of the pin delivery station is made, guide rail 70, solenoid 72 and their associated supports are not required.

Pin elevating member 10 and associated mechanism, as modified above, are operative in the same general manner as the preferred embodiment disclosed in FIGURES 1, 2 and 3. All like members function in like manner.

Pins are received into pockets 30 and elevated therein as described hereinabove. As each successive pocket is rotated past the new location of the pin discharge station, rod 56, due to the gravity bias of weight 62, pivots into position adjacent stop 64, as described hereinabove

60 for the preferred embodiment. When rod 56 is thus pivoted, pin 68, previously secured in pocket 30 by rod 56 as described above, is automatically released and gravitates into pin receiving and aligning device 80. When, during the cyclic operation of the bowling pin 65 spotting machine of which the pin elevating member 10 forms an operative part, it is determined by the control system (not shown) that pins are not to be released at station III, the rotation of pin elevating member 10 is temporarily halted or interrupted until pins 68 are again required by the pin spotting units of the associated machine.

What I claim is:

1. In a bowling pin spotting machine for use with a bowling alley having a pit at one end, mechanism for elevating bowling pins removed from the playing sur-

face of said alley into said pit comprising a rotary member provided with an annular channel and spaced pin carrying portions, means mounting said member for rotation in a substantially vertical plane such that such portions of said channel pass successively through and out of said pit, means for rotating said member, means for moving said pins in said pit into said channel as said successive pin carrying portions thereof pass through said pit, gravity-actuated pin holding members mounted on said channel and associated with each of the pin carrying portions of said channel and operative to coact with said channel and be gravity biased into engagement with pins in said portions in response to the rotation of said member, whereby pins are held in said channel against removal therefrom during the rotation of said channel.

2. The invention as defined in claim 1 including means at a point remote from said pit operative to selectively release said pins held in said channel.

3. In a bowling pin spotting machine for use with a bowling alley having a pit at one end, mechanism for elevating bowling pins removed from the playing surface of said alley into said pit comprising an annular channel, a plurality of pin holding units in said channel, a pin receiving station, a pin discharge station, means for rotating said channel to travel said units in succession to and from said pin receiving station, and to and from said discharge station, means for directing pins into said units in said channel, elongated pendulums, means pivotally mounting one of said pendulums adjacent each of said pin holding units for gravity bias theretoward into pin holding engagement with said pins in said units, and means for maintaining each pendulum in holding engagement with a pin as said pins are elevated to said discharge station.

4. The invention as defined in claim 3 including release means comprising a solenoid, means mounting said solenoid adjacent said discharge station and means for selectively energizing said solenoid such that said solenoid is operative to selectively engage said pendulums whereby said pins held in said units thereby are discharged therefrom.

5. In a bowling pin spotting machine for use with a bowling alley having a pit at one end, a pin elevating mechanism comprising an annular channel provided with a plurality of circumferential recesses, means mounting said channel in said pit for rotation about a substantially horizontal axis with successive recesses thereof passing into and out of said pit, means for rotating said channel, means for delivering pins in said pit from the playing surface of said alley to the successive portions of said channel passing through said pit, said pins being received in said recesses with their longitudinal axis substantially at right angles to the axis of rotation of said channel, elongated rods, means pivotally mounting each of said rods on said channel adjacent each of said recesses, counterweights mounted on the ends of said rods remote from said recesses whereby, in response to the rotation of said mechanism, said rods will be biased by gravity toward said recesses, holding pins in said recesses against removal therefrom during the rotation of said channel and their elevation thereby from said pit, and stop means for controlling the limits of movement of said rods into and out of operative positions with said recesses.

6. The invention as defined in claim 5 including release means comprising a solenoid, means mounting said solenoid adjacent the highest point of the path of travel of said rods as they are rotated on said channel, and means for selectively energizing said solenoid to engage said rods at said point whereby said pins held in said recesses thereby will gravitate therefrom.

7. Pin holding mechanism for use with a rotary pin elevating device of an automatic bowling pin spotting machine comprising clamp means mounted in spaced relation along the length of said pin elevating device, said means being gravity actuated in response to the rotation

of said device with pins in said device, and means on said device and coacting therewith for maintaining said clamp means in holding engagement with said pins in said device against removal therefrom during the rotation of pin elevating device and release means at a predetermined discharge station to selectively disengage said clamp means from said pins for discharge from said device.

8. Pin holding mechanism for use with a rotary pin elevating device of an automatic bowling pin spotting machine having a plurality of pin carrying units comprising elongated rods, means pivotally mounting said rods in spaced relation adjacent each of the pin carrying units of said pin elevating device, means on said rods to effect the gravity bias of said rods toward said units to retain pins therein during the movement of said pins from the pit of a bowling alley to an elevated pin discharge station, means maintaining said rods in pin holding engagement with pins in said units during at least a portion of said movement, and means at said discharge station to selectively release said pins from said units.

9. In a rotatable pin elevating device for use with a bowling pin spotting machine, said device provided with a plurality of pin recesses, pin engaging mechanism comprising elongated pendulums, means pivotally mounting each of said pendulums adjacent each of said recesses whereby said pendulums are operative to gravitate toward said recesses holding pins lodged therein against removal therefrom during their elevation by the rotation of said device, and stop means limiting the extent of movement of said pendulums when in and when out of operative holding position relative to said recesses.

10. In a rotatable pin elevating device for use with a bowling pin spotting machine, said device provided with a plurality of circumferential pin pockets, pin gripping apparatus comprising elongated rods, means pivotally mounting each of said rods adjacent each of said pockets for gravity bias alternately toward and away from said pockets, gripping or releasing pins therein as said device is rotated, and stop means limiting the extent of movement of said pendulums when in and when out of operative holding position relative to said recesses.

11. In a bowling pin spotting machine for use with a bowling alley having a pit at one end, a pin elevating mechanism comprising an annular pin conveying channel provided with a plurality of circumferential recesses, means mounting said channel in said pit for rotation about a substantially horizontal axis with successive recesses thereof passing into and out of said pit, means for rotating said channel, means for delivering pins in said pit from the playing surface of said alley to the successive portions of said channel passing through said pit, said pins being received in said recesses with their longitudinal axes substantially at right angles to the axis of rotation of said channel, elongated rods, means pivotally mounting each of said rods on said channel adjacent each of said recesses, counterweights mounted on the ends of said rods remote from said recesses whereby said rods will be biased by gravity toward said recesses holding pins in said recesses against removal therefrom during the rotation of said channel and their elevation thereby from said pit to a pin discharge station remote from the highest point of travel of said channel, said counterweights being operative by gravity to bias said rods away from said recesses at said pin discharge station to release said pins conveyed thereto in said recesses, and stop means limiting the extent of movement of said pendulums when in and when out of operative holding position relative to said recesses.

12. In a bowling pin spotting machine for use with a bowling alley having a pit at one end, mechanism for elevating bowling pins removed from the playing surface of said alley into said pit comprising an annular channel, a plurality of pin holding units in said channel, a pin receiving station in said pit, a pin discharge station re-

move from the highest point of travel on said channel, a pin transfer device proximate said discharge station, means for rotating said channel to travel said units in succession to and from said pin receiving station, and to and from said discharge station, means for directing pins into said units in said channel, elongated pendulums, and means pivotally mounting one of said pendulums for gravity bias adjacent each of said pin holding units whereby said pins in said units will be held therein by said pendulums as said pins are elevated to said discharge station, and means mounted adjacent said discharge station operative in response to the movement of said channel to disengage said pendulums from said pins held thereby whereby said pins thus released drop out of said units into said pin transfer device.

13. In a bowling pin spotting machine for use with a bowling alley having a pit at one end, a pin elevating mechanism comprising an annular pin conveying channel provided with a plurality of circumferential recesses, means mounting said channel in said pit for rotation in a substantially vertical plane with successive recesses thereof passing into and out of said pit, means for rotating said channel, a pin receiving station in said pit, means for delivering pins in said pit from the playing surface of said alley to said pin receiving station where successive portions of said channel pass through said pit, said pins being received in said recesses with their longitudinal axes substantially at right angles to the axis of rotation of said channel, a pin discharge station positioned between 180 and 270 degrees on the path of travel of said channel from said pin receiving station, elongated rods, means pivotally mounting each of said rods on said channel adjacent each of said recesses, counterweights mounted on the ends of said rods remote from said recesses whereby said rods will be biased by gravity toward said recesses holding pins in said recesses against removal therefrom during the rotation of said channel and their elevation thereby from said pit to said pin discharge station, said counterweights being operative at said discharge station to bias said rods away from said recesses to release said pins elevated therein, and stop means operatively associated with each of said rods for maintaining said rods in pin holding position during at least a portion of the rotation

5 of said channel to said discharge station, and for positioning each of said rods adjacent an empty recess for gravity bias in response to the rotation into pin holding position when said rods travel from said pin receiving station towards said pin discharge station.

14. In a bowling pin spotting machine for use with a bowling alley having a pit at one end, a pin elevating mechanism comprising an annular channel provided with a plurality of circumferential recesses, means mounting said channel in said pit for rotation about a substantially horizontal axis with successive recesses thereof passing into and out of said pit, means for rotating said channel, means for delivering pins in said pit from the playing surface of said alley to the successive portions of said channel passing through said pit, said pins being received in said recesses with their longitudinal axis substantially at right angles to the axis of rotation of said channel, elongated rods, means pivotally mounting each of said rods on said channel adjacent each of said recesses, counterweights mounted on the ends of said rods remote from said recesses whereby, in response to the rotation of said mechanism, said rods will be biased by gravity towards said recesses, holding pins in said recesses against removal therefrom during the rotation of said channel and their elevation thereby from said pit, release means including a solenoid, means mounting said solenoid adjacent the highest point of the path of travel of said rods as they are rotated on said channel, means for selectively energizing said solenoid to engage said rods at said point whereby said pins held in said recesses thereby will gravitate therefrom and stops mounted on each of said rod mounting means operative to limit the extent of gravity bias of said rod in the alternate directions thereof, one of said stops being operative to limit the gravity bias away from its respective pocket such that pins entering therein are unhindered thereby.
